US0D1090834S

(12) **United States Design Patent** (10) **Patent No.:** **US D1,090,834 S**
(45) **Date of Patent:** **** Aug. 26, 2025**

(54) **SOFT TISSUE CUTTING DEVICE**

(71) Applicant: **Sonex Health, Inc.**, Eagan, MN (US)

(72) Inventors: **Darryl E. Barnes**, Eagan, MN (US);
Jay Smith, Byron, MN (US); **Kevin Arnal**, Excelsior, MN (US); **Aaron Keenan**, Austin, MN (US); **Jeffrey King**, Chanhassen, MN (US)

(73) Assignee: **Sonex Health, Inc.**, Eagan, MN (US)

(**) Term: **15 Years**

(21) Appl. No.: **29/891,408**

(22) Filed: **May 5, 2023**

Related U.S. Application Data

(63) Continuation of application No. 29/803,594, filed on Aug. 13, 2021, now Pat. No. Des. 989,961.

(57) **CLAIM**

The ornamental design for a soft tissue cutting device as shown and described.

DESCRIPTION

FIG. 1 is a top perspective view of a soft tissue cutting device.

FIG. 2 is a bottom perspective view of the soft tissue cutting device of FIG. 1.

FIG. 3 is a rear view of the soft tissue cutting device of FIG. 1.

FIG. 4 is a front view of the soft tissue cutting device of FIG. 1.

FIG. 5 is a left side view of the soft tissue cutting device of FIG. 1.

FIG. 6 is a right side view of the soft tissue cutting device of FIG. 1.

FIG. 7 is a top view of the soft tissue cutting device of FIG. 1; and,

FIG. 8 is a bottom view of the soft tissue cutting device of FIG. 1.

The broken lines in FIGS. 1-8 illustrate portions of the soft tissue cutting device that form no part of the claimed design.

1 Claim, 7 Drawing Sheets
